UNITED STATES PATENT OFFICE.

WILLCORD W. COTE, OF HOLYOKE, MASSACHUSETTS, ASSIGNOR OF ONE-HALF TO F. G. BURNHAM, OF HOLYOKE, MASSACHUSETTS.

HOT-STEEL SCRAPER.

1,198,894.

Specification of Letters Patent. Patented Sept. 19, 1916.

Application filed February 16, 1916. Serial No. 78,758.

To all whom it may concern:

Be it known that I, WILLCORD W. Cote, a citizen of the United States, residing at Holyoke, in the county of Hampden and 5 State of Massachusetts, have invented new and useful Improvements in Hot-Steel Scrapers, of which the following is a specification.

My present invention relates to improvements in apparatus for scraping or cleaning metal bars, rods, and the like, and particularly for removing or cleaning the scales or crusts from hot pieces of metal.

The primary object of the invention is to 15 provide an apparatus of this character which is capable of receiving the bars, rods, or other pieces of hot metal with facility and is operative to effectively remove the scales or crusts therefrom quickly and by a simple 20 manipulation of the bar, rod, or other piece of metal:

A further object of the invention is to provide a scraper of this character which is capable of being adjusted readily to accommodate 25 it to metal bars, rods, or other pieces of different sizes and also to adapt the apparatus to rods, bars, or other pieces having cross-sections of different shapes.

To these and other ends, the invention 30 consists in certain improvements, and combinations and arrangements of parts, all as will be hereinafter more fully described, the novel features being pointed out particularly in the claims at the end of the specification.

In the accompanying drawings:—

Figure 1 is a front elevation of a scraper or cleaning apparatus constructed in accordance with the present invention. Fig. 2 40 represents a rear elevation of the same. Fig. 3 represents a section on the line 3—3 of Fig. 2. Fig. 4 represents a section on the line 4—4 of Fig. 2. Fig. 5 is a view 45 similar to Fig. 3, showing diagrammatically the position of the parts when a bar or rod is inserted therein. Fig. 6 is a detail perspective view of one of the movable scraper blades. Fig. 7 is a detail perspective view of one of the studs for holding 50 the movable scraper blades in operative position. Fig. 8 is a detail perspective view of a scraper blade jaw adapted to operate upon round rods or bars.

Similar parts are designated by the same reference characters in the several views. 55

In heating metal rods, bars, or other pieces in furnaces preparatory to forging the same in drop-hammers or presses, scales or crusts form on the surfaces of the bars or rods, and if the bars or rods with the scales or 60 crusts thereon are forged in the dies of a drop-hammer or press, such scales or crusts, which are harder than the heated metal of the bars or rods, are embedded in the surfaces of the bars or rods, rendering the forgings defective. A considerable percentage 65 of loss in forgings results from this cause.

It is the principal object of the present invention to provide an apparatus which is capable of effectively removing these 70 scales or crusts when the heated bars or rods are removed from the furnace and before the same are forged in the dies, the apparatus to be so constructed that it will readily receive the heated bar or rod while the same 75 is held at one end by tongs in the hands of the workman, and the withdrawal of the heated bar or rod will cause the apparatus to thoroughly and effectively remove the scale or crust, the time required for the removal of the scale or crust being so short as to avoid any appreciable cooling of the metal rod or bar in the interval between the removal of the same from the furnace and placing of the same into the forging dies. 85

The preferred embodiment of the invention is shown in the accompanying drawings and will be hereinafter described in detail. It is to be understood, however, that the invention is not restricted to the precise construction shown, as equivalent constructions within the scope of the claims are contemplated.

In the present instance, the apparatus comprises a main plate or frame 1 having 95 an opening 2 therein of a size sufficient to receive the largest bars or rods within the capacity for which the apparatus is designed. The main plate or frame has a lower extension or leg 3 which serves to 100 fasten or secure it to an appropriate support, the leg 3 in the present instance being bent horizontally to form a bracket 4 which may be bolted on the top of a table, bench or other support, and stiffening ribs or webs 105 5 preferably extend between the leg 3 and

the bracket 4 to maintain these parts in rigid relation. Arms 6, 7 and 8 radiate from the central opening 2 in the base plate. At the rear of the base plate or frame are located blades which operate to scrape the scale or crust from the rods or bars. In the construction shown, a blade 9 is fitted at the rear side of the leg 3 and has a scraper edge or jaw 10 which extends across the opening 2 in rear of the base plate. The blade 9 is preferably adjustable to enable the apparatus to accommodate bars, rods, or other metal pieces of different diameters, but when once adjusted is preferably held rigidly in its adjusted position. In the present instance, the blade 9 is provided with longitudinal slots 11, and bolts 12 are provided which extend through the slots 11 and through a slot 13 in the leg 3, each bolt having a head 14 to clamp against the rear surface of the blade 9 and a nut 15 to clamp against the forward side of the leg 3. If desired, the rear face of the blade 9 adjacent to the slots 11 may be serrated, as shown, and the under sides of the heads 14 of the bolts may be correspondingly serrated to prevent shifting of the blade relatively to the bolts when the latter are tightened. To enable the scraper edge 10 of this blade to be removed for sharpening, or renewed, it is preferable to provide the scraper edge for this blade with a separate jaw 16, this jaw being set in the upper end of the blade 9 and removably secured to the blade 9 by screws 17 or equivalent means. At the rear sides of the arms 6, 7 and 8 are arranged slideable scraper blades 18, 19 and 20, these blades being similar in their construction and mode of operation. Each of these blades has a scraper edge 21 which is preferably formed on a jaw 22 which is removably inserted in the inner end of the respective blade and is detachably secured thereto by screws 23 or equivalent means to enable removal of the jaws for sharpening or replacement. Each of these slideable jaws is also formed in the present instance with a slot 24 which extends longitudinally thereof, and a stud 25 is provided which serves to guide and limit the respective slideable blade in its movements, although permitting rearward deflection of the blade when the bar or rod is introduced into the apparatus. Each of these studs in the construction shown has a rectangular head 26 which fits into the slot 24 of the blade, the head 26 being of a size and shape that will permit a limited sliding movement of the blade relatively to the stud, while the sides of the head 26 will coöperate with the sides of the slot 24 and thereby guide the blade in its sliding movements. In order to assist the stud in guiding these blades, lugs 27 are preferably formed on the edges of each of the arms 6, 7 and 8, these lugs being ar-

ranged at the longitudinal edges of the respective blades and thus operating to prevent lateral edgewise displacement of the blades. The head 26 of each stud clamps against the rear side of the corresponding arm 6, 7 or 8, as the case may be, and a rib 28 on the stud projects into a slot 29 in the respective arm of the frame, the stud having a threaded end 30 which extends to the front of the main plate or frame and is there provided with a nut 31 which clamps against the forward side of the base plate, drawing the under side of the head 26 against the rear side of the base plate and in that manner holding the stud firmly in fixed relation to the base plate. The slot 29 in the base plate permits the stud to be adjusted, thereby accommodating the sliding blades to bars or rods of different diameters. In order to prevent shifting of the studs when the same are clamped tightly, the under side of the head 26 is preferably serrated, as shown, and is arranged to coöperate with serrated surfaces formed on the rear side of the base plate at opposite sides of each slot 29 therein. The rib 28 of each stud which fits into the slot 29 prevents turning of the stud when the nut 31 is turned to tighten or release the stud. The slideable scraper blades are not only capable of reciprocating so as to move their scraper edges toward or from the center of the opening 2 in the base plate, but these sliding jaws are also capable of tilting or swinging rearwardly. To permit such movement of the slideable scraper blades, each stud has lugs 32 thereon which engage the rear side of the respective scraper blade at opposite sides of the slot 24 therein.

Means is provided for yieldingly pressing the opposed scraper blades toward one another and for also returning the slideable scraper blades to their normal aligned position after having been deflected or swung rearwardly incident to the introduction of a rod or bar between them. In the present instance, a stud 33 is fixed to each slideable and tilttable scraper blade and also to the relatively fixed blade 9, these studs projecting rearwardly from the blades for a suitable distance, and tension springs 34 are stretched between the adjacent studs 33 in such a manner as to avoid obstructing the opening through which the rod or bar is inserted, the springs, however, operating to perform the dual function of sliding the jaws inwardly or toward one another and of returning these jaws to aligned position after having been deflected or swung rearwardly incident to the introduction of the bar or rod. As shown, the ends of the springs 34 engage the studs 33 toward the rear ends of these studs or at points offset substantially to the rear of the planes of the scraper blades. In order to prevent acci-

dental disengagement of the ends of the springs 34 from the studs, the outer ends of the studs may be curved, as shown, or a cotter pin and washer 35 may be provided 5 on each stud to retain the ends of the springs thereon.

In practice, scraper jaws are used to conform to the cross-section of the bars, rods, or other pieces that are being handled.

- 10 For example, in handling bars or rods which are square or rectangular in cross-section, jaws having straight edges, as shown in Figs. 1, 2 and 6, are used, while in handling bars or rods which are round in cross-section, a jaw such as shown in Fig. 8 may be used, the jaw in this instance having a scraper edge 36 which is concaved appropriately to fit the circumference of the round rod or bar.
- 20 In using an apparatus constructed as hereinbefore described to remove scale or crust from rods or bars, the different blades are adjusted so as to provide an opening between them which is slightly less than the 25 dimensions of the bar or rod which is to be subjected to the scraping operation. To remove the scale or crust from the bars or rods, the same are removed from the furnace usually by tongs, and each heated rod or 30 bar is introduced endwise through the opening 2, and the striking of the end of the bar or rod against the inner ends of the sliding and pivoted blades causes the latter to deflect or swing rearwardly, as shown diagrammatically in Fig. 5. The rod or bar is 35 then introduced for its full length into the apparatus, and it is then pulled out of the same. In pulling the rod or bar forward, the pivoted blades which were deflected 40 when the rod or bar was introduced into the apparatus move forward against the rear sides of the base plate, and the scraping edges on these blades are then supported firmly in position to remove the scale or 45 crust from the bar as the latter is pulled forward.

I claim as my invention:—

1. An appliance of the character described comprising coöperative blades having scraper edges thereon, one of said blades being capable of deflection in a direction transversely of its length when a rod, bar, or the like is inserted between the blades, the blades being also relatively movable toward and from 50 one another to grip the rod, bar, or the like to remove scale therefrom.

2. An appliance for scraping scale from rods, bars, or other pieces of hot metal comprising coöperative blades having opposed scraper edges, at least one of said blades being pivoted to deflect when the rod or the like is introduced between the scraper edges, the blades being relatively movable in a direction toward and from one another and 60 operative to scrape the scale from the bar or

the like as the latter is moved in a direction to withdraw it from between the scraper edges.

3. An appliance for scraping scale from rods, bars, or the like comprising pairs of 70 blades relatively slidable in intersecting paths and having scraper edges at their inner ends conforming to the circumference of the rod or the like, certain of said blades being also pivoted to deflect out of their normal plane of operation to facilitate introduction of the rod or the like between the scraper edges.

4. An appliance for scraping scale from rods, bars, or the like comprising coöperative 80 blades having opposed scraper edges, said blades being relatively reciprocable in a direction toward and from one another and also relatively tilttable out of their normal plane of operation.

5. An appliance for scraping scale from rods, bars, or the like comprising coöperative blades having opposed scraper edges, said blades being relatively reciprocable in a direction toward and from one another and 90 also relatively tilttable out of their normal plane of operation, and means operative to yieldingly resist such tilting.

6. An appliance for scraping scale from rods, bars, or the like comprising coöperative 95 blades having opposed scraper edges, said blades being relatively reciprocable in a direction toward and from one another and also relatively tilttable out of their normal plane of operation, and means acting to 100 move the blades toward one another and to yieldingly resist such tilting.

7. An appliance for scraping scale from rods, bars, or the like comprising coöperative blades presenting opposed scraping 105 edges, one of said blades being held in fixed position, and the blade opposite thereto being movable in a direction toward and from the fixed blade and also capable of deflection in a direction transversely of its length. 110

8. An appliance for scraping scale from rods, bars, or the like comprising coöperative blades presenting opposed scraping edges, one of said blades being held in fixed position, and the blade opposite thereto being 115 movable in a direction toward and from the fixed blade and also tilttable out of the plane of such movement.

9. An appliance for scraping scale from rods, bars, or the like comprising coöperative blades presenting opposed scraping edges, one of said blades having means for securing it in different adjusted positions, and the coöperating blade being movable away from such blade and also displaceable 120 from its normal plane of operation.

10. An appliance of the character described comprising a frame, coöperative scraper blades arranged to lie against one side of the frame, studs connected to the 130

- frame and permitting reciprocating and tilting movements of the blades relatively to the frame, and means acting normally to move the blades toward one another and to 5 yieldingly resist tilting of the blades.
11. An appliance of the character described comprising a frame having an aperture therein for the insertion of the rod or other piece to be scraped, coöperative 10 scraper blades having at their inner ends scraping edges overlying said aperture, means for attaching the blades to the frame whereby they may move in a direction toward and from one another and their inner 15 ends may tilt rearward away from the frame, and means acting to move the opposed blades toward one another and to yieldingly hold the inner ends of the blades forwardly against the frame.
12. An appliance of the character de- 20 scribed comprising a frame having an aperture therein for the insertion of the rod or other piece to be scraped, a scraper member arranged at the under side of said aperture and having means for securing it to the 25 frame to support the rod or the like introduced into said opening, and coöperative scraper members movable in a direction toward and from the center of said aperture to coöperate with the circumference of such 30 rod.

In testimony whereof, I have hereunto set my hand in presence of two subscribing witnesses.

WILLCORD W. COTE.
